MODULATION SYSTEM

Robert L. Drake, Chicago, Ill., assignor to Bendix Radio Corporation, Chicago, Ill., a corporation of Delaware

Application January 31, 1938, Serial No. 187,791

4 Claims. (Cl. 179—171.5)

This invention relates in general to circuits for electric discharge devices and more particularly to circuits in which the character of the output currents is utilized to determine or limit the flow of space current within the device. The invention also relates particularly to a push-pull type of circuit in which a pair of discharge devices are maintained in balanced relationship.

An object of the invention is to provide a circuit wherein the output of an electric discharge device is determined by the presence of some predetermined frequency at the input of the device. Where, for example, the input to a vacuum tube includes alternating voltages of different frequencies, it may be desired to cut down the total output of the circuit when a voltage of some one frequency is present, and such may be accomplished by a circuit of this invention.

Another important object of the invention is to provide means for automatically balancing a pair of discharge devices when these are connected in push-pull relation. When tubes are connected in push-pull arrangement, it is necessary for good operation that the space currents passed by the tubes be equal in magnitude, and if this is not the case distortion or faulty operation will result. It is desired to prevent unbalanced operation even though the tubes should have different gain characteristics.

A further object is to provide means for correcting the unbalance of discharge devices in push-pull arrangement through control effected by currents of one frequency, this means being unaffected by currents of other than this frequency. It is also desired that the control for effecting equalization between the devices be sensitive so as to effect an exact balance and prevent all error due to unbalances as far as this is possible. Other objects and advantages will be apparent later in the specification. Embodiments of the invention are illustrated in the accompanying drawing in which—

Figure 1 is a circuit diagram of a balanced modulator embodying a principle of this invention for maintaining the tubes in balance;

Figure 2 is a circuit diagram of a balanced modulator constituting another embodiment of the invention; and

Figure 3 is a circuit diagram showing yet another embodiment of the invention wherein novel means of control are effected in but a single discharge device.

As illustrated in Figure 1, the apparatus includes a pair of triodes A and B, each having a cathode, an anode and a grid. The cathodes

are connected together and to ground through the control circuit C. Circuit C comprises an inductor 10 and a capacitor 11 connected in parallel relation between ground and cathodes. The anodes of tubes A and B are connected together through the primary of the output transformer 12, and the mid point of this primary winding is connected through the plate battery 13 to ground. The output circuit of tube A may be followed from the potential source 13, through half of the primary winding on transformer 12 to the anode of tube A, and from the cathode of A through circuit C to the other terminal of the potential source. Similarly the output circuit of tube B may be followed from the potential source 13, through half of the primary winding on transformer 12 to the anode of tube B, and from the cathode of B through circuit C to the other terminal of the potential source.

The input to tubes A and B is derived from two circuits, one of which may contain voltages of carrier frequency and the other of which may contain voltages of the modulating frequency. The carrier frequency circuit, designated as S₁ in Figure 1, has its one side grounded and has its other side connected through blocking condensers 14 and 15 to the grids of both tubes A and B. The other circuit for providing the modulating frequency and designated in the drawing as S₂, has therein an alternator 16 and includes the primary of transformer 17. The alternator 16 is illustrated merely to show a source of alternating current and any means may be used which will provide the desired modulating frequency. The secondary of transformer 17 has its end terminals connected through resistors 18 to the grids of tubes A and B, the resistors being provided to substantially prevent the flow of carrier current in the path of the transformer secondary. As here shown, the grid bias is provided by the battery 19 connected between the mid point of the secondary winding of transformer 17 and ground. It is understood that circuit S₂ might be coupled to the grid circuits of tubes A and B in other suitable ways.

Considering first the carrier frequency input of the tubes, it will be seen that the carrier input circuit may be followed from the side of circuit S₁ not grounded to the grids of both tubes A and B, then through circuit C, and return by ground to the other side of the carrier circuit S₁. As here shown the carrier impulses are fed to each of tubes A and B in the same phase; that is, a positive impulse of this carrier will

appear simultaneously on the grids of each tube. The input circuits of modulating frequency may be traced from the secondary 17s of transformer 17 to the grid of tube A, and from the cathode 5 of this tube through circuit C, and return to winding 17s through battery 19; and similarly from the other terminal of winding 17s to the grid of tube B, and from the cathode of this tube through winding C, and return to winding 10 17s through battery 19.

It will be apparent that this modulating frequency is impressed on tubes A and B in opposite phase relation and tubes A and B will be rendered more conducting at alternate half cycles 15 of the modulating frequency.

The control circuit C is tuned to be resonant at the modulating frequency and its impedance therefore increases very sharply when there exists in the common output circuit path of the two 20 tubes a current of the modulating frequency. It is an important feature of this invention that the voltage drop across this parallel resonant circuit is impressed in the grid-cathode circuit of the tubes in such a manner as to equalize the space 25 currents in the two tubes. This function of circuit C will appear more clearly after consideration of the current and voltage conditions in the apparatus at initially unbalanced condition.

Assume, for the purpose of explanation, that 30 tubes A and B have different gains, the tube A having a tendency toward greater amplification of impulses. Because the modulating frequency is fed to tubes A and B in opposite phase relationship, the modulating frequency component of 35 the tube outputs will be in opposite phase relationship, and the current of this frequency flowing between the cathode of one tube and ground will oppose the current of this frequency flowing between the cathode of the other tube and 40 ground, causing the magnitude of the current of this frequency flowing through circuit C to be equivalent to the difference of the space currents of this frequency in the two tubes. The difference in space currents of the modulating frequency, 45 then, is made to build up a voltage across circuit C which is substantial. This alternating voltage is 180 degrees out of phase with respect to the modulating frequency on the grid of tube A, and in phase with the modulating frequency on the 50 grid of tube B. Consequently, this voltage is subtractive with respect to the modulation potential on the grid of tube A, and additive with respect to the modulation potential on the grid of tube B. Since the negative swings of the modulation 55 potential may carry the grids to the plate current cutoff region, the negative half cycles may be disregarded. The positive swings of modulation potential on the grid of tube A will be reduced in amplitude by the value of the voltage developed across circuit C, and positive swings on tube B will be increased by this value of developed voltage. This adjustment causes the space current in tube A to diminish and the space current in tube B to increase and serves to bring the space 60 currents flowing in each of the tubes to equal 65 magnitude which is the condition of balance.

The circuit C is very sensitive to even a slight unbalance, for only a small difference in space currents in the two tubes is effective to build up 70 a substantial voltage across it, due to the fact that the parallel resonant circuit has a very high impedance at the resonant frequency.

From the above explanation it will be apparent that when the tubes are in themselves perfectly 75 balanced, the circuit C will have no effect, nor

will it present any substantial impedance which would be detrimental to the operation of the apparatus; but that when the tubes are not in themselves perfectly balanced, the circuit C will operate automatically to insure balance through control by the modulating frequency and without impeding the flow of carrier frequency current in the output circuit other than for balancing it between the two tubes.

The modification shown in Figure 2 demonstrates a second scheme for balancing the outputs of tubes connected in push-pull relation. In this arrangement, the cathodes are connected together and the anodes are connected through the primary of the output transformer in the same 15 manner as described in connection with the embodiment of Figure 1. In the path connecting the cathodes of the tubes with the mid point of the output transformer winding is the potential source 30 which supplies plate potential, and also 20 the primary of transformer 31. The secondary of transformer has its terminals connected to the inner ends of secondary windings 32 of the transformer 33 corresponding with transformer 17 of the first described embodiment. The mid point 25 of the secondary of transformer 31 is connected through the biasing battery 34 to ground. In this arrangement a vacuum tube might be substituted for the transformer 31 as the translating means coupling this branch of the output to 30 the grid circuits. Preferably the translating means used here should be such as to cause only small differences of space current in the two tubes to produce substantial differences in the grid voltages, and this is effected by having a translating 35 device which has the higher terminal voltage at its secondary side.

Clearly there will be current flowing through the primary side of the translating means only when the space currents of tubes A and B are 40 not equal in magnitude, and voltages will be built up at the secondary of the translating means to equalize the space currents only to such an extent as is necessary to effect balanced condition.

Figure 3 illustrates a further modification of 41 the invention employing only one electric discharge device. The input to the apparatus as here shown is through the primary of the input transformer 40. The grid or input circuit of the tube T includes biasing battery 41, the secondary of input transformer 40, the circuit C', and the cathode of tube T. The output circuit of the tube includes anode and cathode of the tube, plate battery 42, the primary of output transformer 43 and circuit C'. This type of circuit 50 may be used wherever it is desired to cut off or diminish the output of the tube when some certain frequency is fed into it. Whenever the frequency to which the circuit C' is tuned to be resonant, is fed into the input of the tube, this sets up a relatively high voltage drop across this circuit which in turn makes the grid of the tube more negative with respect to the cathode, thus diminishing the space current which can pass between anode and cathode. When any other frequency is fed into the tube T, there is very low impedance across circuit C', and the grid-cathode voltage is not affected by it.

Though in the embodiments of Figures 2 and 3, the pair of space discharge devices A and B are shown as separate tubes having independent electrodes, these devices may be combined in one tube or envelope in which case a single electrode may comprise the cathodes of both devices.

It is obvious that other embodiments of the

invention may be constructed and many changes may be made in the construction of the embodiments herein described without departing from the spirit of the invention.

5 The foregoing detailed description has been given for clearness of understanding only, and no unnecessary limitations should be understood therefrom, but the appended claims should be construed as broadly as permissible in view of the prior art.

10 I claim:

1. In modulating apparatus, a pair of electric discharge devices arranged in push-pull relation, each of said devices having an anode, a cathode, and a grid, means for varying at one frequency the potentials of said grids with respect to their associated cathodes and in the same phase relation, means for varying the potentials of said grids with respect to their associated cathodes in different phase relation and at another frequency, and means responsive only to space current in said devices of substantially said other frequency for equalizing the total space current flowing in said devices.

2. In modulating apparatus, a pair of electric discharge devices arranged in push-pull relation, each of said devices having an anode, a cathode, and a grid, means for varying at one frequency the potentials of said grids with respect to their associated cathodes, means for varying the potentials of said grids with respect to their asso-

ciated cathodes at another frequency, and means responsive to a difference of plate current of the same frequency in said devices for equalizing the total space current flowing in said devices, said last-mentioned means including an electrical circuit which presents a low impedance to space current of said one frequency but high impedance to space current of said other frequency.

3. Apparatus as set forth in claim 2 in which said electrical circuit includes an inductance and 10 a capacitance arranged in parallel in the anode-cathode circuits of said devices, said circuit being parallel resonant at said other frequency.

4. In modulating apparatus, a pair of electric discharge devices each having an anode, a cathode and a grid, a conductive path connecting said cathodes, a conductive path connecting said anodes, a third path connecting each of said paths, said third path including a source of potential and a control circuit, said control circuit 15 being parallel resonant at a predetermined frequency and input circuits for each of said devices, each of said input circuits including said control circuit and the grid and cathode of one of said devices, said control circuit being responsive to a difference in space current in said devices of said predetermined frequency to alter the potential of said grids with respect to their associated cathodes for equalizing space current 20 in said devices.
